UNITED STATES PATENT OFFICE.

MOSES D. HEYMAN, OF NEW YORK, N. Y.

BAND-CHUCK.

1,158,216.

Specification of Letters Patent.

Patented Oct. 26, 1915.

Application filed March 18, 1915. Serial No. 15,284.

To all whom it may concern:

Be it known that I, MOSES D. HEYMAN, a citizen of the United States, and a resident of the city of New York, borough of Brooklyn, in the county of Kings and State of New York, have invented a new and Improved Band-Chuck, of which the following is a full, clear, and exact description.

Among the objects of the invention is to provide a work holding chuck of a simple, light and reliable mechanical nature and which, therefore, may be produced and sold at a comparatively low cost.

Another object of the invention is to provide a chuck, the immediate holding portion of which is a flexible circular band adapted to snugly engage practically all the way around the work being turned, whereby all danger of damaging the work by crushing, indenting or otherwise marring the same will be avoided.

A still further object of the invention is to provide a jaw member or gripping device for a chuck adapted to be manipulated by the rotation of a simple member, means being provided to cause the operation of the gripping member for its purpose without disturbing the alinement of the work.

The foregoing and other objects of the invention will hereinafter be more fully described and claimed and illustrated in the drawings forming a part of this specification in which like characters of reference indicate corresponding parts in all the views, and in which—

Figure 1 is a vertical transverse section on the line 1—1 of Fig. 2; and Fig. 2 is a vertical longitudinal section on the line 2—2 of Fig. 1.

The several parts of this device may be made of any suitable materials, and the relative sizes and proportions, as well as the general design of the mechanism, may be varied to a considerable extent without departing from the spirit of the invention hereinafter more fully described and specifically claimed.

Referring more particularly to the drawings I show at 10 a casing of substantially cylindrical form and carried concentrically upon an arbor 11 at one end. The other end of the casing is normally closed by a face plate 12 secured in place as by screws 13 tapped into the peripheral flange 14 of the casing. The face plate 12 is provided with a central opening 15.

The main gripping element of the chuck consists of a flexible band 16 of any suitable strong elastic material and preferably faced with a layer of leather, felt or some other suitable cushioning material 17 for the purpose of preventing the abrasion or marring of a piece of work which may be finished or highly polished at the end being held by the device.

The band 16 is shown in its extended form or position and is adapted to be contracted to cause it to grip the work. If a bar, tube or rod of much smaller diameter is to be connected to the chuck, a bushing, indicated at B, of leather or other suitable material may be introduced, as shown in Fig. 1, to act as a filler between the band and the work.

The means I prefer to employ to adjust the band to vary its circumference includes a rotary shaft or bolt 18 journaled in bearings 19 and 20 in the flange 14 adjacent one side of the casing, said bolt having right and left threads 21 and 22 adjacent its middle portion with which coöperate a pair of blocks 23 and 24. These blocks extend inwardly toward the band and each of them is bifurcated and straddles a lug 25 secured to or formed on the adjacent end of the band 16. The bifurcated portion of each block is provided with vertical slots 26, the longer axes of which are at right angles to the direction of movement of the blocks due to the rotation of the bolt 18. Connection between the blocks and the lugs 25 is had through pins 27 which extend through the slots of the blocks and through the lugs 25 in directions parallel to the axis of the chuck, said pins substantially fitting the shorter diameters of the slots 26.

In other words, with the movement of the blocks toward and from each other along the bolt, the pins 27 will be correspondingly moved in both directions. There being no lost motion, therefore, between the pins and the lugs 25 or between the pins and the blocks considered in the direction of movement of the blocks, the ends of the band will be moved toward and from each other in accordance with the adjustment of the blocks and at the same rate of speed.

While the ends of the band are moving toward each other and the effective circumference of the band is being decreased with a corresponding shortening of the diameter thereof, the bottom portion of the band is moved toward the center, and but for special

features provided herein, such movement of the bottom portion of the band would be greater than the decrease in radius due to the contraction of the band. In other words, 5 with the lugs 25 moved toward each other, there will not ordinarily follow the corresponding inward movement thereof in accordance with the decrease in radius of the band. To compensate for this circumstance, 10 I extend the ends of the pins into parallel grooves 29 formed in the opposed inner faces of the front and rear portions of the casing. Each of these grooves comprises two curves arranged at a slight angle to each other, as 15 shown in Fig. 1, the character of the curve and the amount of angle being determined by the extent and direction of movement of the pins toward each other. In the form indicated, the pins are moved upwardly 20 slightly as they begin their movement toward each other, due to the fact that in the open position of the band the ends of the band stand at considerable distance below the actual circumference of the band; hence, 25 when the pins begin to move toward each other, said band ends have a certain upward movement, but such movement continued there is, due to the contraction of the circumference, a downward movement of the 30 pins as they come close to each other. The form of the grooves, therefore, is such that they compensate for the compound movements of the pins, or, in other words, the grooves are so designed that they positively. 35 cause the pins to move in such paths that the band remains always substantially concentric with the casing.

At 30 I show a counterweight secured in the bottom of the casing as by means of a 40 screw 31 to counterpoise the weight of the bolt 18 and parts carried thereby. I wish it to be understood that the terms "upward" and "downward" and similar terms employed throughout the specification are to be 45 interpreted in a relative sense and not as limitations.

While the work is adapted to be held automatically centered by the mere adjustment of the band, yet it may be desirable under 50 certain circumstances, when the chuck is being operated at a high speed for instance, for some positive means to lock the band concentric with the shaft and casing. Hence, after the application of the band to 55 the work, I may adjust a series of set screws 32 radially into contact with the outer surface of the band to steady the same and hold it positively in centered position.

While the foregoing description covers but 60 two lugs 25 connected to the band with a corresponding number of guide pins 27, it is obvious that under certain circumstances or conditions I may use additional guide lugs or pins coöperating with the band at various 65 points. As an illustration of such addi-

tional guide features, I show at 25' a guide lug secured to the middle portion of the band and having a guide pin 27' extending therethrough and guided along a pair of straight radial slots 29'. This construction 70 may be used either with or without the counterweight 30, and if the additional lug 25' is used, the intermediate set screw 32 may be shortened for coöperation with the outer end of such lug. 75

I claim:

1. In a device of the character set forth, the combination of a casing comprising a rear wall, a peripheral flange and a face plate parallel to the rear wall and secured to 80 the flange, said face plate having an opening concentric with the casing, said face plate and rear wall having a pair of parallel grooves formed in their opposed inner faces, a flexible band constituting a gripping 85 member adjacent said face plate opening and surrounding the axis of the casing, and means guided along said grooves to cause the ends of the band to approach or recede from each other. 90

2. In a device of the character set forth, the combination of a hollow casing, a flexible gripping band mounted within and concentric with the casing, said band being split and having lugs extending from the adjacent ends thereof, and means coöperating with the casing and acting upon said lugs to cause the band to expand or contract, said means acting also to maintain the band in 95 its concentric relation to the casing. 100

3. In a device of the character set forth, the combination of a circular casing, a split band arranged concentric coaxially with the casing, a bolt journaled in one side of the 105 casing and having right and left threads thereon, a pair of blocks connected to the ends of the band and mounted upon the threaded portions of the bolt whereby upon rotation of the bolt the band will be contracted or expanded, and means coöperating with said band ends to maintain the band concentric with the casing irrespective of its circumferential adjustment. 110

4. In a device of the character set forth, the combination of a casing, a split band of flexible material constituting a gripping member arranged concentrically of the casing, a bolt journaled in the casing at one side of its center and in a direction transverse to its axis, said bolt having right and left threaded portions, a pair of blocks mounted upon said threaded portions of the bolt and movable thereby toward or from each other upon rotation of the bolt in the casing, said blocks having slots formed in their inner ends with the longer axes of the slots perpendicular to the direction of movement of the blocks, a pair of lugs connected to the ends of the band, pins extending through the lugs and through the block slots, and means 115 120 125 130

acting positively upon the pins to cause the band to remain in its concentric relation to the casing irrespective of the changes in diameter of the band.

5. In a device of the character set forth, the combination of a hollow cylindrical casing, a flexible split gripping band arranged concentrically therein, means arranged within one side of the casing to increase or decrease the circumference of the band and maintain it in its concentric relation, and a counterbalance secured in the other side of the casing to counterpoise the weight of said adjusting means.
10. In a device of the character set forth, the combination of a hollow cylindrical cas-
15. 6. In a device of the character set forth,

ing, a flexible gripping split band arranged therein, means acting through the side of the casing and upon the ends of the band to increase or decrease its effective circumference, and a series of set screws extending radially through the periphery of the casing and against the outer surface of the band to positively lock the same in concentric relation to the casing.

20. In testimony whereof I have signed my name to this specification in the presence of two subscribing witnesses.

25. MOSES D. HEYMAN.
